UNITED STATES PATENT OFFICE.

FERNAND THOMAS, OF PARIS, FRANCE, ASSIGNOR TO DUNKLEY COMPANY, OF KALAMAZOO, MICHIGAN.

MACHINE FOR STEMMING CHERRIES AND OTHER FRUIT.

Application filed September 29, 1921. Serial No. 504,101.

To all whom it may concern:

Be it known that I, FERNAND THOMAS, a citizen of the Republic of France, residing at Paris, France, have invented certain new and useful Improvements in Machines for Stemming Cherries and Other Fruit, of which the following is a specification.

This invention relates to improvements in machines for stemming cherries and other fruits.

The objects of the invention are,

First, to provide special means for the distribution of the cherries;

Second, to provide improved means of stemming clusters of cherries, and

Third, to provide improved means of stemming the single cherries after the clusters have been eliminated and separated.

Objects pertaining to details and economies of construction and operation will definitely appear from the detailed description to follow. I accomplish the objects of my invention by the devices and means described in the following specification. The invention is clearly defined and pointed out in the claims.

A structure which is a preferred embodiment of my invention is fully illustrated in the accompanying drawing, forming a part of this application, in which:

Fig. I is a detail side elevation view, partially in section and partially diagrammatic, showing the entire assembly of my invention.

Fig. II is a detail view through the shaker conveyer, taken on line *a—a* of Fig. I.

Fig. III is a detail side elevation view, partially in section, on an enlarged scale, of the cluster stemming mechanism and means.

Fig. IV is a detail elevation view of a portion of the cluster elevating means as seen from the right of Figs. I and III.

Fig. V is an enlarged detail view of the cluster stripping comb *i*.

Fig. VI is an enlarged detail side elevation view of the mechanism for stemming the single fruits.

Fig. VII is a detail transverse sectional view of the structure appearing in Fig. VI.

Fig. VIII is a plan view of the roller parts with the troughs and brushes omitted, showing the driving means therefor.

In the drawing similar reference charac-

ters refer to similar parts throughout the several views, and I wish to say in this behalf that letters are used instead of figures to correspond to a corresponding French patent.

The distributing means is characterized by the combination of a cylinder having longitudinal grooves intended to receive the fruit and a movable shutter forming part of the bottom of the feed hopper, the free edge of which remains constantly in contact with the cylinder, preventing any crushing of the fruit. A brush parallel to the cylinder and above the same regulates the quantity of fruit admitted in each of the grooves.

Below the cylinder is a shaker frame that uniformly spreads the fruit to pass the same to the next operation of stemming the clusters.

The device for stemming the clusters is an endless belt or chain disposed obliquely upward to carry the fruit from the discharge end of the shaker frame. The endless belt or chain is provided with upwardly inclined hooks with blunt ends on which the cherry stems straddle as they are poured out or thrown over from the shaking frame. These hooks bring the cherry clusters to combs *i* which strip the fruit from these multiple stems, which stems are thus collected by the hook and delivered into suitable discharge troughs.

The stemming of the single cherries is accomplished by the series of inclined troughs, the bottom of each trough having a longitudinal slit. The single cherries not being engaged by the cluster stemming device descend into a suitable hopper and are discharged into these slightly inclined troughs at the upper ends. Endless belt brushes with spaced tufts are disposed above and substantially parallel with each trough and advance the fruit by rolling it in such a way that the stems roll down and project into the slots. A pair of rolls is disposed beneath each slot and engage and pull off the stems, and the cherries pass on and are discharged into a hopper, and thence delivered to the pitting machine *y*, here indicated by diagram.

Considering the drawings in detail, in Fig. I the distributing means is seen to comprise a feed hopper *a* having an inclined bot-

tom of which the part *b* is supported by the hinge *b'*. The free end of this movable part or shutter rests upon the periphery of the distributing cylinder *c*, the top of which 5 turns from the said shutter. The cylinder *c* is provided with longitudinal grooves *c'*. It is thus clear that in this manner fruit such as cherries cannot pass between the cylinder and shutter and therefore none can be lost 10 or crushed.

Above the cylinder *c* and parallel therewith is disposed a brush *d* revolving as indicated by the arrow. The brush is placed on adjustable supports, not shown, so that it 15 can be raised and lowered to effect the proper control of the amount delivered by the distributing cylinder. Feeding of the machine is thus regulated.

The fruit falls from the cylinder *c* to the 20 shaker frame *e* which oscillates quite rapidly. The actuation is effected by a pitman connection to the eccentric shaft *e'*. The hopper is mounted on suspension springs or in any other appropriate manner.

25 The object of the frame *e* is to spread the shaking fruit uniformly and deliver it to the stemming means. The bottom of this shaker may be smooth, perforated, or it may be corrugated as indicated at *e*² in corrugations parallel lengthwise thereof, as shown 30 in Fig. II. In case the cluster stemming device is not required, this grooved shaker could guide the fruit into the corresponding troughs where stemming of single fruit 35 takes place, as herein described.

The cluster stemming device consists of an inclined canvas belt running on shafts *g*¹ *g*² and carrying hooks *h* upwardly inclined, of proper form and spacing, with 40 rounded ends so as not to damage the fruit.

Above the hooks and co-operating with them are the combs *i*, shown in Fig. V. The fruit, as cherries, that comes from the shaker *e* falls on this canvas *f*, the single 45 fruit passes between the hooks and is guided by an apron or hopper *j* and falls into the stemming trough slots *k*, hereafter described.

The cluster cherries, whether two or more, are engaged by the upwardly moving hooks 50 *h* which carry them up and the hooks pass through the combs *i*, which combs engage and detach the fruit from the stems. The stems detach themselves from the hooks on the descending course of the canvas and fall 55 into the discharge conduit *l* (Fig. III). Instead of mounting the hooks *h* on a canvas as described, they may be mounted on transverse strips *m*, indicated in detail in Fig. IV, which are carried by the chain *n* driven 60 by sprockets *m*¹ *m*² mounted on shafts *g*¹ *g*².

In this structure a partition *o* extends to a certain height in the zone of discharge of the fruit that falls from the shaker frame *e*. Where this is done the fruit that 65 is stemmed by the combs *i* passes into the

empty space above the partition *o* and falls directly into the discharge conduits *p* which discharges it from the stemmer. In this way the cluster cherries that have been stemmed are separated from the single 70 cherries and do not pass down into the trough slots *k*, and this tends to augment the capacity of the machine and save undue handling of these cherries. The slotted troughs *k* for the stemming of single fruit 75 are inclined as shown in Fig. I. A plurality of these troughs is employed, corresponding to the capacity of the machine. The slotted troughs are provided in their bottoms with slits *k*¹ (Fig. VII). For cherries these 80 slits are approximately one centimeter wide.

Above each slotted trough and parallel to it are traveling brushes *q* of suitable length and suppleness which are mounted on the endless chain *r* carried by sprockets *r*¹ 85 mounted on the shafts *r*² *r*³. One shaft, say *r*², can be actuated by the shaft *s* (see Fig. I). These brushes sweep the bottom of each slotted trough and carry and roll the fruit in such a way that the stems pass 90 through the slots in the bottom. The brushes are spaced at suitable intervals to allow the fruit to tumble and roll as it descends through the troughs.

Underneath each slot and very near are 95 placed two parallel rolls *t*¹ *t*². One of these rolls is actuated, for example, by the use of gears *u*¹ *u*². The latter is keyed on a shaft *u* driven by the principal shaft by means of an intermediate shaft *r*². 100

The stems of the fruit that pass in the slits *k*¹ are engaged by the rolls *t*¹ *t*² and pulled off. The fruit is retained in the troughs and carried to the end of them by the combined effect of the brushes and the 105 incline.

The rolls *t*¹ *t*² can be covered with rubber or with any kind of rubberized coating, or present a work surface of metal. They can be smooth, knurled or have designs of various forms to assure a sure hold of the stems. One of them, or both of them, can be equipped with a projecting spiral *v* in order to facilitate the action of stemming. 110

The stemmed fruit falls into a hopper *w* 115 which conducts it to the pitting machine *y* (Fig. I).

By referring to Fig. I it will be seen that the principal shaft *s* may drive the cylinder *c*, the brush *d*, the shaft *e*¹, the shaft *r*² of the brushes and through this one the shaft *q*¹ for the hooks *h* and the shaft *u* of the stemmer roll, through chains or belting or other means. 120

The condition of the fruit may not require all of the above instrumentalities. It may be that there are few clusters; if so the cluster stemming means might be dispensed with. The devices illustrated in Figs. VI, VII and VIII are also capable 125 130

of stemming cluster fruit, and it would be possible to dispense with the features appearing in Figs. III, IV and V. However, the uses of the structure appearing in Figs. 5 III, IV and V assure the best results and a surer operation of the entire machine.

The structures here illustrated are more or less diagrammatic and are only given as examples. Forms and dimensions and materials employed and the arrangement of details can be varied in all cases without changing the principle of the invention. I desire to claim the invention in the specific form illustrated, and also broadly, as pointed 15 out in the appended claims.

Having thus described my invention, what I claim as new and desire to secure by Letters Patent is:

1. In a cherry stemming machine, the 20 combination of a feed hopper, a discharging cylinder with longitudinal corrugations therein to receive the fruit, a movable hinged bottom, the free edge of which is disposed to rest upon the said cylinder, an adjustable 25 rotary brush disposed above the said cylinder to regulate the amount of fruit carried by said cylinder, a shaking hopper beneath said cylinder containing longitudinal corrugations, an upwardly inclined conveyer with 30 forwardly disposed hooked fingers thereon to receive fruit from said shaker and engage the stems of the clusters of fruit, a stripping comb disposed above said shaker and in position to coat with the hooks on said conveyer, a 35 to stem the clusters of fruit, discharging troughs for the stems and fruit associated with said conveyer; a hopper beneath said conveyer, slotted inclined troughs beneath said hopper positioned to receive the said 40 fruit with single stems, tufted brushes on endless conveyers disposed and spaced and arranged to move and advance the fruit in said troughs, and pairs of stripping rolls under each of the 45 said slots to pull the stems, as specified.

2. In a cherry stemming machine, the combination of a feed hopper, a discharging cylinder with longitudinal corrugations therein to receive the fruit, a movable hinged bottom, the free edge of which is disposed to 50 rest upon the said cylinder, and an adjustable rotary brush disposed above the said cylinder to regulate the amount of fruit carried by said cylinder.

3. In a cherry stemming machine, the combination of a feed hopper, a discharging cylinder with longitudinal corrugations therein to receive the fruit, a movable hinged bottom, the free edge of which is disposed to 55 rest upon the said cylinder, and a rotary brush disposed above the said cylinder to regulate the amount of fruit carried by said cylinder.

4. In a cherry stemming machine, the combination of a feed hopper, a discharging cyl-

inder with longitudinal corrugations therein to receive the fruit, a movable hinged bottom, the free edge of which is disposed to rest upon the said cylinder, a rotary brush disposed above the said cylinder, and a shaking hopper beneath the said cylinder containing longitudinal corrugations.

5. In a cherry stemming machine the combination of a feed mechanism comprising a shaking hopper with longitudinal corrugations therein, an upwardly inclined conveyer with forwardly disposed hooked fingers thereon to receive fruit from said shaker and engage the stems of the clusters of fruit, a stripping comb disposed above 75 said shaker and in position to coat with the hooks on said conveyer to stem the clusters of fruit, discharging troughs for the stems and fruit associated with said conveyer, a hopper beneath said conveyer, slotted inclined troughs beneath said hopper positioned to receive the said fruit with single stems, tufted brushes on endless conveyers disposed and spaced and arranged to move and advance the fruit in said troughs, and pairs of stripping rolls under each of the 80 said slots to pull the stems, as specified.

6. In a cherry stemming machine the combination of a feed mechanism comprising a shaking hopper with longitudinal corrugations therein, an upwardly inclined conveyer with forwardly disposed hooked fingers thereon to receive fruit from said shaker and engage the stems of the clusters of fruit, a stripping comb disposed above 95 said shaker and in position to coat with the hooks on said conveyer to stem the clusters of fruit, a hopper beneath said conveyer, slotted inclined troughs beneath said hopper positioned to receive the said fruit with single stems, tufted brushes on endless conveyers disposed and spaced and arranged to move and advance the fruit in said troughs, and pairs of stripping rolls under each of the 100 said slots to pull the stems, as specified.

7. In a cherry stemming machine the combination of a feed mechanism comprising a shaking hopper with longitudinal corrugations therein, an upwardly inclined conveyer with forwardly disposed hooked fingers thereon to receive fruit from said shaker and engage the stems of the clusters of fruit, and a stripping comb disposed above 105 said shaker and in position to coat with the hooks on said conveyer to stem the clusters of fruit.

8. In a cherry stemming means the combination of slotted inclined troughs to receive the fruit, tufted brushes on endless conveyers disposed and spaced and arranged to move and advance the fruit in said troughs, and pairs of stripping rolls under each of the 115 said slots to pull the stems, as specified.

9. In a cherry stemming means the combination of slotted inclined troughs to receive 120

the fruit, brushes on endless conveyers disposed and spaced and arranged to move and advance the fruit in said troughs, and pairs of stripping rolls under each of said slots to 5 pull the stems, as specified.

10. In a cherry stemming machine the combination of hook devices for engaging

the stems of cherries, means for carrying said hook devices upward, and stripper means coacting therewith to stem the 10 cherries.

In witness whereof, I have hereunto set my hand and seal.

FERNAND THOMAS. [L.S.]
